CLAIM

I claim the ornamental design for the module for a tattoo and permanent make-up applicator, as shown and described.

DESCRIPTION

FIG. 1 is a perspective view of the disposable detachable module for apparatus for applying a tattoo or permanent make-up showing my new design;

FIG. 2 is a top plan view thereof;

FIG. 3 is a bottom plan view thereof;

FIG. 4 is a right view thereof;

FIG. 5 is a left view thereof;

FIG. 6 is a rear plan view thereof; and,

FIG. 7 is a front plan view thereof.
